Primary Examiner — Wan Laymon*(74) Attorney, Agent, or Firm* — Nixon & Vanderhye, P.C.(57) **CLAIM**

The ornamental design for a "video projector," as shown and described.

DESCRIPTION

FIG. 1 is a top, right perspective view of a video projector in accordance with our new design;

FIG. 2 is a front elevation view thereof;

FIG. 3 is a rear elevation view thereof;

FIG. 4 is top plan view thereof;

FIG. 5 is a bottom plan view thereof;

FIG. 6 is a right-side elevation view thereof;

FIG. 7 is a left-side elevation view thereof;

FIG. 8 is a top, rear perspective view thereof;

FIG. 9 is a cross section taken along the line 9-9 in FIG. 2;

FIG. 10 is a cross section taken along the line 10-10 in FIG. 2; and,

FIG. 11 is a cross section taken along the line 11-11 in FIG. 4. The broken line showing portions of a video projector is included for the purpose of illustrating environmental structure and forms no part of the claimed design.
